UNITED STATES PATENT OFFICE

100,755

DESIGN FOR AN AUTOMOBILE

Lynn Brodton, Collingswood, N. J.

Application May 22, 1935, Serial No. 56,966

Term of patent 7 years

To all whom it may concern:

Be it known that I, Lynn Brodton, a citizen of the United States and a resident of Collingswood, in the county of Camden and State of New Jersey, have invented a new, original, and ornamental Design for Automobiles, of which the following is a specification, reference being had to the accompanying drawings forming a part thereof and in which

I claim:

The ornamental design for an automobile substantially as shown.

LYNN BRODTON.
